UNITED STATES PATENT OFFICE

2,492,793

TYPEWRITER PLATEN CONTROL
MECHANISMRoy E. Gearhart, Kansas City, Mo., assignor of
one-half to Allen Chambers, Kansas City, Mo.

Application January 14, 1946, Serial No. 641,126

6 Claims. (Cl. 197—114)

1

This invention relates to improvements in typewriter platen control mechanisms and has for its principal object a typewriter platen control wherein the platen may be moved to any predetermined point for writing by simply turning the platen knob.

In the operation of various standard makes of typewriters the spacing of the lines is usually single, double and triple, that is, if the normal line space is $\frac{1}{6}$ of an inch, then the operator by operating the shift lever may move the platen through $\frac{1}{6}$ of an inch, $\frac{1}{3}$ of an inch or $\frac{1}{2}$ of an inch spaces, depending on the adjustment of the operating means. Any intermediate spacing less than a full normal line space must be made by operating the platen-release mechanism and moving the platen independently of the shifting means by adjusting the platen knobs. When the platen is thus shifted the lines previously written will usually be out of register with the new positioning of the platen.

It is the principal object of the present invention to provide means for operating the platen, having detents whereby the platen may be moved through relatively short spaces, said spaces being equal, fractional divisions of the normal line space, whereby the platen may be positively positioned to substantially register with any typed line on the paper. The accuracy of registration will depend on the number of equal divisions into which the normal line space is divided. The larger the number of divisions, the more accurate the registrations will be.

Another object of the invention is the provision of a ratchet or detent wheel having spring actuated engaging means whereby the platen may be positioned in any predetermined fractional division of the normal line space by simply rotating the platen by means of the attached hand knobs.

Another object of the invention is the provision of a platen control whereby the typewriting operation may be started and continued from substantially any point on the platen.

Another object of this invention is the provision of a platen control having a plurality of detent stops for a single predetermined line space whereby the platen may be positioned to substantially register the writing mechanism with any previously written line.

A further object of the invention is a spiral gear drive between the platen shaft and a manually operable driving means.

Other objects are simplicity and economy of construction, ease and accuracy of operation and

2

adaptability for use in dividing the rotary movement of the platen into substantially microscopic divisions.

With these objects in view as well as other objects which will appear in the following specification, reference will be had to the drawings, wherein:

Fig. 1 is a fragmentary plan view of a typewriter structure including the platen and platen mounting and a platen control mechanism embodying this invention.

Fig. 2 is an enlarged, sectional view taken on line II—II of Fig. 1.

Fig. 3 is an irregular, sectional view taken on line III—III of Fig. 2.

Fig. 4 is an irregular, sectional view taken on line IV—IV of Fig. 2 with parts shown in dotted lines.

Fig. 5 is an enlarged, fragmentary sectional view taken on line V—V of Fig. 1.

Fig. 6 is a sectional view similar to that shown in Fig. 3 with the operating lever arm moved to an intermediate position.

Fig. 7 is an inverted, fragmentary view of the operating lever.

Fig. 8 is an irregular, vertical sectional view taken on line VIII—VIII of Fig. 2.

Fig. 9 is a partially broken away plan view of the back lash take-up worm gear shown in solid lines in its normal position and in dotted lines in the worm engaging position.

Fig. 10 is a fragmentary, sectional view taken on line X—X of Fig. 4.

Fig. 11 is an inverted, plan view of the top disk.

Fig. 12 is an inverted, plan view of the top plate and associated parts.

Fig. 13 is a plan view of the driving disk.

The drawings show only such parts of the combined typewriter structure as are necessary for an understanding of the manner in which the platen control may be applied to the typewriter. In the operation of a typewriter it is highly desirable to be able to start and continue writing at substantially any point on the paper by simply rotating the platen to position by means of the platen knobs.

Throughout the several views like reference characters refer to similar parts and the numeral 50 designates a typewriter platen fixedly mounted for rotation with a shaft 22. One end portion of shaft 22 is mounted in a bearing 24 from which it may be removed by simply lifting the shaft upwardly. The other end portion of shaft 55 22 is mounted in a bearing 26 which is integral

with a gear housing 28. This housing is grooved on its opposite sides at 30 and 32 to receive tongues 34 of the typewriter carriage frame 36.

When so positioned in the bearings 24 and 26 the platen may be rotated in the usual manner of a typewriter platen to feed paper to the proper position for typewriting thereon. Tension rollers 38 operate in conjunction with the platen to position the paper during the writing operation.

Mounted in gear housing 28 is a split, back lash take-up worm gear 40 having two offset gear portions 42 and 44. Gear portion 42 is rigidly attached to shaft 22 by means of a set screw 46, and gear portion 44 is normally carried in offset relation to portion 42 by means of a spring 48 which is anchored at 50 in the hub 52 of gear portion 42 and is tensioned to normally urge the teeth 54 and 56 of gear portions 42 and 44 out of registered alignment. Worm gear 40 is driven by a worm 58 mounted on a bearing post 60, which is rigidly mounted in gear housing 28 as clearly shown in Fig. 2. When the worm teeth are forced to position in the worm gear the teeth of gear sections 42 and 44 will be forced into substantially registering relation against the action of spring 48 which will tend to absorb all back lash and secure the platen against over-riding (see Fig. 9). As the gear teeth become worn spring 48 will cause relative movement of gear teeth 54 and 56 to facilitate proper fitting of the teeth of the gear and worm to absorb all back lash. Referring to Figs. 2 and 8 it will be noted that spring 48 extends through an enlarged opening 55 formed in hub 52 to tightly engage in a hole 57 formed in gear section 44. The spring 48 is preferably made of piano wire and is of sufficient length to permit flexing to move the gear sections to avoid objectionable back lash, without fatiguing the spring. A spacing sleeve 49 mounted on shaft 22 and secured thereto by set screw 51 serves to prevent axial movement of gear section 44.

The worm 50 is provided with a long hub 62 having at its upper end a concentrically mounted annular disk 64. This disk is press-fitted on the hub, rotatable therewith and has a recess 66 formed in its upper surface to receive a rigidly fitted internal ratchet wheel 68 having a continuous line of teeth of equal pitch.

An operating lever 70 having a hub 72 is rotatably mounted on bearing post 60 with the hub extended into recess 66, and the lever arm 74 extending outwardly from the disk 64 to present a suitable finger grip 76 for the operator. An operating pawl 78 is pivoted at 79 to the under side of lever arm 74 to ride in recess 66. The free end 80 of pawl 78 is constantly urged outwardly by spring 82 which is securely attached to lever arm 74 at 84.

The upper face of gear box 28 is provided with a fixed plate 86 notched at 88 to form a recess 90 for the reception of an arm 92 having a fixed pin 94 which is pivotally mounted in a hole 96 formed in the wall of the gear box 28 (see Fig. 10).

This arm 92 carries at its free end a depending pin 98 on which is mounted for rotation a roller 100 which is adapted to engage between adjacent teeth of ratchet wheel 68 to serve as a detent to insure the proper line register. A spring 102 anchored at 104 in plate 86 is formed to contact the edge of arm 92 to constantly urge roller 100 to the seated position between said ratchet teeth. This action of the roller 100 will

thus tend to always bring the platen to the desired line spacing position.

The top plate 106 is rigidly attached to the gear housing 28 by means of screws 108 to cover the roller arm 92 and has an annular portion 110 which is disposed concentrically about bearing post 60. This annular portion 110 has depending offset arcuate portions that provide stop 112 for the limiting of the back movement of the operating lever and a stop 114 that limits the forward movement of the operating lever. That portion of annular portion 110 between stops 112 and 114 is positioned above disk 64 a sufficient distance to form a slot 116 to permit of free working movement of the operating lever arm 74 therein.

Top plate 106 is provided with a boss 118 bored at 120 to receive the body of plug 122 and having a reduced hole 124 to receive the neck 126 of plug 122 which extends above base 118 to receive the lever arm 128 which is secured thereto by means of pin 130. An eccentrically disposed pin 132 carried by the lower end of said plug extends into recess 66 in the path of travel of arm 92 and is normally positioned to permit free movement of the arm. When it is desired to make arm 92 inoperative, lever 128 is moved to position the pin 132 in the position shown in dotted lines in Fig. 4. When so positioned the pin will rest against a shoulder stop 134 formed in said arm.

Mounted concentrically about bearing post 60 is an annular disk 136 which registers with annular member 110 and disk 64 and is held in position by shouldered sleeve 138 rigidly secured to post 60 by set screw 140. Sleeve 138 is recessed at 142 to register with an annular flange 144 formed on top of operating lever 70 to present a compartment 146 to receive a lever operating spring 148. The upper end of spring 148 is offset parallel with its axis at 150 to fit into a hole 151 formed in sleeve 138 and its other end is formed radially at 152 to engage a notch 154 formed in flange 144. Spring 148 is so set that it will always return the operating lever 74 to the normal or retracted position.

Referring to Fig. 3 which shows a section through disk 136, it will be noted that the disk is recessed at its under side to receive an annular ring 156 having a series of ratchet teeth 158 and an arcuate cam 160 of less radius than said series of ratchet teeth and disposed in diametrically disposed relation thereto. The ratchet teeth 158 are subtended by like radial angles as are teeth 68 and as shown are like radial distances from the axis of the bearing post 60. It is a requirement that the radial degrees of the lead of the teeth in the two sets of ratchet teeth be the same regardless of their relative radius for the purpose of proper timing of the operation of the operating pawl 78 as hereinafter set forth. A vertically disposed pin 162 mounted in operating pawl 78 adjacent its free end rides on cam 160 when the operating lever 74 is in the retracted position thus holding the pawl out of engagement with ratchet teeth 68; however, as the lever arm 74 moves forwardly, the pin 162 will drop off the end 164 of the cam and the spring 82 will force it into engagement with the ratchet teeth to drive the platen through the desired degrees. In order to vary the degree of movement of the platen the disk 136 is rotated through the desired degree to position the end 164 of the cam relative to the retracted position of the operating pawl 78. By moving the disk 136 clockwise the platen will be

caused to move through a greater degree since the pin 162 will drop from cam 160 sooner on its forward movement thus traveling a greater distance with the pawl 78 engaging ratchet teeth 68. Means for holding disk 136 in a set position is provided in the form of a pawl 166 pivoted intermediate its ends on a pin 168 mounted in an ear 169 integral with top plate 106 and provided at its one end with a roller 170 which engages between adjacent teeth of ratchet teeth 158. A spring 171 rigidly anchored at 172 in the wall of ring 110 is formed to engage one end of pawl 166 to constantly urge the other end of the pawl against the series of ratchet teeth 158 whereby the disk 136 may be forced to any desired position by engaging the operating handle 174. An indicator pointer 176 mounted rigidly on sleeve 130 is adapted to register with the graduations 178 formed on the top surface of disk 136 (see Fig. 1).

Each end of platen shaft 22 is provided with an operating knob 180 which is secured thereto by means of set screws 182 and by means of which the platen 20 is manually rotated.

In the operation of this machine the operator engages the handle 174 to move disk 136 so that the index finger 176 will register with the desired graduation 178. As previously set forth the operating lever arm 74 moves through the same arc to engage the back stop 112 and the forward stop 114, and as shown in the Figure 3 the cam 160 is set so that the operating pawl 80 will drop into the engagement and move the ratchet 68 through a space equivalent to three of the ratchet teeth so that the platen will be rotated through one predetermined standard space, and when so positioned, the typewriter may be operated to write what is normally termed a single spaced letter. As the handle 174 is operated to set disk 136 the detent ratchet teeth 158 will be engaged by the roller 170 which will positively position said disk so that the index pointer 176 will be in exact alignment with the desired graduation 178. This machine is constructed to operate for single and double spacing only; however, it might be easily increased to triple spacing without any change in the general operation.

When the roller 170 is in registering position between adjacent teeth of the ratchet 158 the roller 100 of arm 92 will be in register between adjacent teeth of driving ratchet 68. In other words, the unit radial angle adjustment of disk 136 is always equivalent to the radial angle adjustment when the operating ratchet wheel is moved one tooth. For this reason it is not material as to the radial distance of the detents from the axis of rotation of the disk, but is only dependent upon the angle of the arc through which the detent is moved. When the disk 136 is set as just described the operating parts will take the position shown in Figure 3 so that as the lever arm 74 is moved to rotate the operating pawl 62, the pawl pin 162 will ride on the cam face 160 so that the pawl 78 will override the internal ratchet teeth 68 until it drops off the shoulder 164 of the cam to engage a ratchet tooth at the center of its stroke. When so engaged the ratchet cam will be rotated three ratchet teeth or through one predetermined standard space. When it has moved through the space of three of the ratchet teeth the arm 74 will contact the stop 114 thereby definitely limiting its movement.

It will be noted that the point of drop of the pawl 78 to the tooth engaging position is not critical since it may drop into a tooth and then

move up to the tooth engaging position before actually starting the driving operation. The driving of the ratchet wheel 68 also drives the worm or spiral gear 56 through a like arc which in turn drives the spiral gear 42 thus driving the platen shaft to which the platen 20 is rigidly attached. If for any reason the operator desires to move the platen without operating the lever 74 he simply grips the platen knobs 180 and turns the platen against the action of the detent 102. If it is desired to move the platen independently of the detent arm 92 he simply throws the lever 128 in the direction indicated by the arrow in Figure 1 until the pin 132 takes the position shown in dotted lines in Figure 4, thus permitting a free movement of the platen to any desired position.

When the platen has been moved to the desired position the operator simply moves the lever 128 back to its original position thus releasing the arm 92 so that the roller will engage between adjacent teeth of the ratchet wheel 68. It is quite apparent that should the roller 100 of the arm 92, when released, be out of register with said ratchet teeth, it will immediately force the ratchet wheel to rotate through a slight degree to facilitate a proper registration.

Due to the fact that the normal standard spacing of a typewriter is substantially $\frac{1}{6}$ of an inch and the movement of the ratchet wheel 68 to move the platen $\frac{1}{6}$ of an inch is the space of three of said ratchet teeth, the movement of the ratchet wheel through the space of one tooth would move the platen through the space of $\frac{1}{18}$ of one inch; therefore, should the roller 100 of arm 92, when released, be substantially in radial alignment with the point of one of the teeth of ratchet wheel 78, the greatest distance that it would be required to move said ratchet wheel to the seated position would be through an angle that would move the platen $\frac{1}{36}$ of an inch. Due to the relatively long distance of travel of the pawl 78 in moving the platen through one space or $\frac{1}{6}$ of an inch, it will be apparent that the operating force required is considerably reduced as compared with the force required to operate the present-day typewriter wherein the pawl moves the driving ratchet but one tooth. By moving disk 136 clockwise as viewed in Figure 1, the cam 160 will be moved to a position whereby the operation of the lever 14 will move the platen but $\frac{1}{3}$ of a space or $\frac{1}{18}$ of an inch. By moving the disk 136 anti-clockwise one graduation the platen will be moved through one and one-third spaces or $\frac{1}{6}$ of an inch.

Other variations in the stroke of the platen may be varied in like steps from $\frac{1}{18}$ of an inch to $\frac{1}{3}$ of an inch.

It is quite apparent that the limit of change might be varied by simply adding a larger range of travel of the operating lever; furthermore, the fineness of the distance of travel might be varied by adding more graduations and corresponding detents between the adjacent standard spacing.

What I claim and desire to protect by Letters Patent is:

1. In a typewriter platen control mechanism a platen shaft carrying a platen and mounted for rotation in a platen carriage frame, a worm gear mounted on said platen shaft, a worm mounted for rotation on a bearing post and carrying a concentrically positioned internal ratchet wheel, an operating arm mounted for rotation on said bearing post, a spring actuated pawl carried by said operating arm within said ratchet wheel and adapted to engage and move said ratchet wheel, and adjustable means to hold said pawl out of

engagement with said ratchet wheel for a predetermined portion of the travel of said operating arm whereby the degree of operation of said worm gear is determined.

2. In a typewriter platen control mechanism a platen shaft carrying a platen and mounted for rotation in a platen carriage frame, a driven gear mounted on said platen shaft, a drive gear operatively engaging said driven gear and mounted for rotation, an internal ratchet wheel rotatable with said drive gear, a pawl adapted to be rotated within and concentrically of said ratchet wheel to engage and move said ratchet wheel, and adjustable means operable to vary the ratchet engaging stroke of said pawl as said pawl is successively moved through like arcs.

3. In a typewriter platen control mechanism a platen shaft carrying a platen and mounted for rotation in a platen carriage frame, an internal driving ratchet wheel carried for rotation on a bearing post carried by said frame, means operatively interconnecting said ratchet wheel with said platen shaft whereby the latter is rotated to drive said platen, an operating lever carried on said bearing post for oscillatory movement between stops rigidly associated with said frame, a pawl carried pivotally by said operating arm and disposed within said internal ratchet wheel to engage the teeth thereof, the teeth of said ratchet wheel being spaced so that rotation of a single tooth turns the platen the smallest desired unit, and an adjustable cam whereby said pawl is held out of engagement with said ratchet wheel during any desired portion of the oscillation of said operating lever.

4. In a typewriter platen control mechanism a platen shaft carrying a platen and mounted for rotation in a platen carriage frame, an internal driving ratchet wheel carried for rotation on a bearing post carried by said frame, a reducing gear train operatively interconnecting said ratchet wheel with said platen shaft whereby the latter is rotated to drive said platen, an operating lever carried on said bearing post for oscillatory movement between stops rigidly associated with said frame, a pawl carried pivotally by said operating arm and disposed within said internal ratchet wheel to engage the teeth thereof, the teeth of said ratchet wheel being spaced so that rotation of a single tooth turns the platen the smallest desired unit, and an adjustable cam whereby said pawl is held out of engagement with said ratchet wheel during any desired portion of the oscillation of said operating lever.

5. In a typewriter platen control mechanism a platen shaft carrying a platen and mounted for rotation in a platen carriage frame, an internal driving ratchet wheel carried for rotation on a bearing post carried by said frame, means operatively interconnecting said ratchet wheel with said platen shaft whereby the latter is rotated to drive said platen, a spring detent associated with said frame to engage the teeth of said ratchet wheel to permit only stepped rotation thereof, an operating lever carried pivotally on said bear-

ing post for oscillatory movement between stops rigidly associated with said frame, a pawl carried pivotally by said operating arm, said pawl being disposed within said ratchet wheel and normally urged into engagement with the teeth thereof, the teeth of said ratchet wheel being so spaced that rotation of a single tooth turns the platen the smallest desired unit of rotation, and a cam ring disposed concentrically with said bearing post and forming a cam adapted to hold said pawl out of engagement with said ratchet wheel during a predetermined portion of the movement of said operating lever, said cam ring being manually rotatable about said bearing post in steps registering with the teeth of said ratchet wheel.

6. In a typewriter platen control mechanism a platen shaft carrying a platen and mounted for rotation in a platen carriage frame, an internal driving ratchet wheel carried for rotation on a bearing post carried by said frame, means operatively interconnecting said ratchet wheel with said platen shaft whereby the latter is rotated to drive said platen, a spring detent associated with said frame to engage the teeth of said ratchet wheel to permit only stepped rotation thereof, an operating lever carried pivotally on said bearing post for oscillatory movement between stops rigidly associated with said frame, a pawl carried pivotally by said operating arm, said pawl being disposed within said ratchet wheel and normally urged into engagement with the teeth thereof, the teeth of said ratchet wheel being so spaced that rotation of a single tooth turns the platen the smallest desired unit of rotation, a cam ring disposed concentrically with said bearing post, said cam ring being formed to present an internal cam adapted to hold said pawl out of engagement with said ratchet wheel during a predetermined portion of the movement of said operating lever and having a series of internal teeth formed therein of equal angular pitch with the teeth of said ratchet wheel, and a spring actuated detent carried by said frame and engaging the teeth of said cam ring, said cam ring thereby being rendered manually rotatable in steps corresponding to the angular pitch of said ratchet wheel to regulate the number of units through which said ratchet wheel is turned for each stroke of the operating lever.
